TREATMENT OF HYDROCARBON OILS

Jacque C. Morrell, Chicago, Ill., assignor to
Universal Oil Products Company, Chicago, Ill., a
corporation of South Dakota

No Drawing. Application September 17, 1931,
Serial No. 563,460

4 Claims. (Cl. 196—36)

This invention relates to the treatment of hydrocarbon oils and refers more particularly to the treatment of relatively low boiling cracked oils although distillates from the straight run or 5 non-cracking distillation of petroleum may also be treated.

More specifically the invention has reference to the treatment of hydrocarbon vapor mixtures containing substantial amounts of components 10 boiling within the range of commercial gasoline and in its most particular aspect has reference to the treatment of the vapors produced by cracking relatively heavy hydrocarbon oils, an improved process being disclosed which makes 15 possible and practicable the production of finished gasolines directly from the cracking process, thus modifying the usual steps involving the chemical treatment of light cracked distillates and their rerunning to produce gasoline so that 20 the liquid treating and subsequent rerunning operation can be eliminated with resultant savings in chemical reagents and the cost of the rerunning distillation.

Petroleum distillates, especially cracked distillates, contain undesirable compounds, presumably of a highly unsaturated character, which render them unstable with respect to color, 25 gum-forming properties and knock rating. Such distillates tend to deposit polymer or gum-like substances while in storage, causing a drop 30 in color which may render the product unsaleable. The development of gums may also prevent proper operation of the motor by plugging or gumming up the fuel feed lines, carburetor, 35 valves and other parts of the motor. Other objectionable compounds such as those of sulphur, nitrogen and the like may be present in such distillates, and it is among the objects of this invention to remove, or reduce to a minimum, the 40 objectionable substances present in petroleum distillates.

One of the important and desirable developments in petroleum refining is the direct production of a marketable distillate from the 45 cracking process. Many attempts have been made to employ refining agents for this purpose, particularly directed towards the use of sulphuric acid which, for the most part, have been unsuccessful because they have failed to take into consideration the physical and chemical properties 50 of sulphuric acid under the conditions of refining. The use of sulphuric acid as a refining agent antedates the drilling of the first oil well in the United States, but heretofore it has been 55 successfully applied as a refining agent to pe-

troleum and its products only while in the liquid state.

The following table taken from the 1913 Edition of the Manufacture of Sulphuric Acid and Alkali by Lunge, a standard work on the subject, 60 shows the relationship between the boiling point and concentration of sulphuric acid:

Table I

Percent H ₂ SO ₄	B. Pt. °F.	
95.3	567	
92.8	536	70
90.4	507	
88.7	494	
86.6	467	
84.3	442	
81.8	425	
80.6	407	
78.9	398	
77.5	387	
75.3	362	
73.9	356	
71.5	344	
69.5	336	
67.2	320	
65.4	318	
64.3	305	80
59.4	290	
56.4	272	
50.3	255	
45.3	245	
41.5	239	
34.7	230	
27.6	225	
15.8	218	85
8.5	215	

From the above table it is evident that at a given temperature and at each temperature the sulphuric acid exists at a definite concentration 90 and that irrespective of the concentration of the sulphuric acid fed into a system at a given temperature if it is more dilute than that indicated by the concentration for the corresponding temperature it will concentrate to the given 95 concentration; also that for each set of conditions there is a corresponding minimum concentration. For example, if an approximately 8% solution of sulphuric acid is fed into a tower, the average temperature of which is approximately 360° F., neglecting the partial pressures 100 of the steam and oil vapors, the sulphuric acid introduced will concentrate to approximately 75% and under these temperature conditions such a concentration of sulphuric acid will immediately attack and destroy the unsaturated hydrocarbons in the immediate vicinity, resulting in an off-colored overhead product of high 105 gum content and in a charring of the derivatives of sulphuric acid in the hydrocarbons, plugging 110

up the column and rendering the process inoperative. The above indicates only approximately the conditions existing in the tower but is sufficient to illustrate the trend and direction of the reaction and explain why previous attempts to refine in the manner described have been unsuccessful.

It is well known that concentrations of sulphuric acid which may be even substantially non-reactive at ordinary temperatures are highly destructive in their reactions at elevated temperatures. Hence while it is desirable to treat petroleum distillates in the vapor state in order to avoid the expense of redistilling the product, it is imperative that a method of treatment be provided which will enable one to definitely control the concentration and consequently the rate and kind of reaction at the elevated temperatures of treatment. The present invention accomplishes this aim in a new and novel manner which will be hereinafter more fully described.

In one specific embodiment the invention comprises treating hydrocarbon oil vapors, especially cracked vapors, with aqueous solutions containing essentially sulphuric acid, a sulphate or acid sulphate and an oxidizing salt or salts of oxidizing acids, or the oxidizing acids themselves.

The proportions of the three groups of treating reagents which may thus be used in solution may be varied over a wide range depending upon their mutual solubility, the particular chemical action required, the temperature and pressure under which the treatment is conducted and other controllable details of operation. In regard to the sulphates or acid sulphates which may be employed, those of the alkali metals, the alkaline earth metals or the heavy metals may be used depending upon their solubility and the other features mentioned. The salts of oxidizing acids mentioned may be such salts as chromates, dichromates, permanganates, chlorates, nitrates, hypochlorites, molybdates, tungstates, bromates, iodates, etc., either alone or in suitable admixtures determined again by their solubility, their treating effect and their availability.

It will be obvious to those familiar with the chemical nature of the oxidizing salts mentioned that their reaction with heated hydrocarbon vapors will be extremely vigorous unless modified by suitable dilution. It will also be evident to those familiar with the physics and chemistry of solutions that it is difficult to determine the exact nature of the ions present in solutions or the nature of their union with each other except as evidenced by chemical and electrochemical effects characteristic of the solutions and the nature of the solid salts deposited as the solutions are progressively concentrated. The main and essential feature of the present invention lies in providing a series of treating solutions which may be used in treating cracked vapors to controllably oxidize, polymerize and desulphurize them.

In conducting operations comprised within the scope of the invention, hydrocarbon vapors from any source, for example, direct from a cracking process and in general from any distillation process including substantially atmospheric pressure distillation of crudes or rerun distillations upon primary distillates may be passed through towers containing filling or baffling material if desired either countercurrent to or concurrent with a solution containing regulated proportions of sulphuric acid, acid sulphates, and oxidizing salts. The treating solution may be introduced in the form of a spray or mist from sprays,

atomizers or nozzles to insure intimate contact with the vapors undergoing treatment or it may be, for example, introduced unto the top tray of a series of superimposed plates to flow downwardly countercurrent to a rising stream of vapors. In some cases it may be sufficient to introduce the vapors into the bottom of a pool of treating reagent so that their upward passage therethrough effects the desired treatment. Other efficient contacting or mixing devices such as orifice columns may be employed. In any case of operation the treating reagent may be introduced, the vapors withdrawn and the sludge reaction products removed continuously by utilizing any of the well known treating and fractionating devices common to the oil industry.

Treatments may be employed alone or as a step along with other separate treatments such as treatment with fullers earth and preliminary or final neutralization or sweetening of the vapors with ammonia or liquid alkali solutions, sodium plumbite, etc., to insure the neutralization of acidic compounds and subsequent separate treatments may also be employed. Other types of treatments which may be conducted as preceding or succeeding steps following the application of the treating process of the invention are such treatments as those accomplished by the use of metals, metal oxides, lime, etc.

In a preferred operation of the process the vapors treated are preliminarily fractionated so that their boiling range approximates that of commercial gasoline so that the reagent is not wasted upon portions of the vapor mixture which are too heavy for use as motor fuel.

The sludge from the treatment may at times be recirculated, particularly in the case of treatments involving counterflow of reagent solution and vapors through a filled tower, such recirculation being employed to insure maximum efficiency in the use of the particular solution employed. It is further contemplated to insert a regeneration step so that sludge produced may be used as a basis for making fresh reagent. For example, it may be diluted to separate and partially hydrolyze dissolved and emulsified oils and acid organic compounds, the aqueous solution concentrated to desired strength and replenished by the addition of calculated amounts of the chemicals necessary to restore it to the proper composition for its effective use.

It is recognized that the employment of powerful oxidants such as the salts of chloric, perchloric, permanganic and other acids may seem at first thought to be a revolutionary step in the treatment of cracked hydrocarbon vapors, but the present invention provides for the safe and controllable utilization of these stronger oxidizing properties by using the oxidizing compounds in a more or less dilute condition, this dilute condition being due principally to the use of relatively large amounts of neutral or slightly acid salts in the treating solutions. For example, the original treating solution may contain 50% by weight of sodium acid sulphate, approximately 10% by weight of sulphuric acid and 3% of either sodium chromate or sodium permanganate. Such a solution may be readily utilized under the conditions of pressure and temperature obtaining in a fractionating column employed as the final step in the cracking of heavier oils without becoming concentrated to the point of deposition of solid materials, whereas a weak solution of sulphuric acid containing the same proportion of permanganate but no acid sulphate would be

come concentrated due to evaporation until a concentration of sulphuric acid is reached which would exert a very destructive and charring effect upon the cracked vapors and produce effects far beyond those desirable.

Owing to the possible variations in composition of treating solutions which may be used in conducting treatments characteristic of the invention the number of operations and results obtainable therefrom might be considerably multiplied. However, one characteristic example will be illustrative and will make evident at once the practicability and commercial advantages of the process.

15 The example selected may be one concerned with the treatment of substantially end point vapors from cracking plant operating upon a heavy gas oil charging stock produced from California crude. These vapors may be passed upwardly through a tower equipped with necessary contact surfaces counterflow to a treating solution of the following approximate composition:

	Percent
25 Sulphuric acid H_2SO_4	43
Sodium acid sulphate $NaHSO_4$	25
Sodium permanganate $NaMnO_4$	4
Water	28

30 Without vapor phase treatment gasoline condensed from the cracking plant after a light caustic wash would normally possess the following properties:

35 Gravity A.P.I.	54
Gums by copper dish method	400 mg.
Saybolt color	10
Sulphur	0.4%

40 The gasoline produced after applying the process of the invention to the vapors prior to their condensation will be recovered in only slightly reduced yield, say, 1% less than that

45

120

50

125

55

130

60

135

65

140

70

145

75

150

normally recoverable without treatment and will possess the following properties:

Gravity A. P. I.	54.2
Saybolt color	+30
Color after 4 hrs. exposure to sunlight	26
Gums	8 mg.
Sulphur	0.16%

The temperature at the top of the treating tower may be approximately 300° F., and the pressure substantially atmospheric or slightly superatmospheric.

The foregoing descriptive material and example will serve to define the nature of the present invention and indicate its applicability in the refining of cracked vapors but the description and examples are illustrative only and specific only in regard to the cases described and should not therefore be considered as constituting limitations upon the broad scope of the invention.

I claim as my invention:

1. In the refining of hydrocarbon distillates, the step which comprises treating the same with an aqueous solution of sulphuric acid containing a sufficient quantity of a sulphate to prevent undue concentration of the solution and an oxidizing agent selected from the group consisting of the inorganic oxidizing acids and the salts thereof.

2. The step as defined in claim 1 further characterized in that said sulphate is an acid sulphate.

3. In the refining of hydrocarbon distillates, the step which comprises treating the same with an aqueous solution of sulphuric acid containing a sufficient quantity of a sulphate to prevent undue concentration of the solution and a salt of an inorganic oxidizing acid.

4. In the refining of hydrocarbon distillates, the step which comprises treating the same with an aqueous solution of sulphuric acid containing a sufficient quantity of an acid sulphate to prevent undue concentration of the solution and a salt of an inorganic oxidizing acid.

JACQUE C. MORRELL.
